UNITED STATES PATENT OFFICE.

CHARLES A. LINDSTRÖM, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

CAR-TRUCK.

1,160,295.

Specification of Letters Patent. Patented Nov. 16, 1915.

Application filed November 7, 1910. Serial No. 591,029.

To all whom it may concern:

Be it known that I, CHARLES A. LINDSTRÖM, a citizen of the United States, residing at No. 138 Stratford avenue, Pittsburgh, E. E., in the county of Allegheny and State of Pennsylvania, have invented certain new and useful Improvements in Car-Trucks, of which the following is a specification.

10 An object of the present invention is to provide changes in what is known to railway engineers as the "Fox" type of truck for railway rolling stock or in trucks of similar type, to increase the strength of the 15 truck without increasing its size or changing its proportions.

Trucks of the "Fox" type comprise essentially rigid side frames which, at their central portions, support the truck bolsters or 20 transoms, or both, and which transmit the load therefrom to the car axles through the medium of yokes or U-shaped pedestals at the ends of the rigid side frames and which pedestals receive and are supported 25 by springs mounted on the axle journal boxes, said pedestals also forming a bearing in which the journal boxes slide vertically. Usually and preferably side frames are made by pressing steel plates, but sometimes they are built up of plates and commercial sections.

"Fox" trucks have been extensively used, especially for railway freight cars and locomotive tenders, the tender trucks differing 35 from the freight car trucks principally in the provisions for the tender truck of a movable truck bolster mounted between truck transoms and elliptical bolster supporting springs projecting through perforations in 40 the truck side frames, while the "Fox" truck for freight cars ordinarily has no movable bolster, its center bearing plate being mounted directly on rigid transoms extending from side frame to side frame. Hence, also, the 45 "Fox" freight car truck has no elliptical springs projecting through the side frames.

In both freight car and tender "Fox" trucks, there are helical springs located between the pedestals and the tops of the journal boxes. The tender trucks are provided 50 with the additional elliptical springs to make the truck more flexible and adapt it to compensate for the great variation in load carried by a locomotive tender, due to consumption of fuel and water, so that no mat-

ter what the load on the tender is, shocks incidental to travel are absorbed.

An example of the "Fox" type of freight car truck is illustrated in Patent No. 468,146, granted to D. L. Barnes, Feb. 2, 1892; an example of the "Fox" type of truck especially adapted for locomotive tenders is found in Patent No. 505,159, granted to S. Fox, Sept. 19, 1893; both of these patents showing side frames of pressed steel. An example of a "built-up" side frame in this type of truck is found in the patent to C. T. Schoen, No. 553,431, granted Jan. 21, 1896.

A specific object of the present invention is to strengthen the side frame of the "Fox" type of truck to adapt the truck for use under railway rolling stock of greater capacity and weight without increase in proportions of the truck.

The invention will be described and illustrated in connection with what has been above described as especially adapted for use as a tender truck, but when described it will be readily appreciated that the improvements are equally applicable to all trucks of the "Fox" or similar type. Only so much of a "Fox" truck will be described as is necessary to illustrate the invention, reference being had to the accompanying drawings in which like characters refer to like parts, and in which

Figure 1 is a sectional side elevation of the "Fox" truck. Fig. 2 is a sectional rear elevation of the same. Fig. 3 is a sectional plan view of half of the same. Fig. 4 is a detail face view of one of the truck pedestals. Fig. 5 is an edge view of the same. Fig. 6 is a vertical section of the same on the line 6—6 of Fig. 4. Fig. 7 is a bottom plan view of the pedestal. Fig. 8 is a horizontal section on the line 8—8 of Fig. 4. Fig. 9 is a like view on the line 9—9 of Fig. 4 and through the pedestal bolt. Fig. 10 is a side elevation of the pedestal bolt bracket. Fig. 11 is a top plan view of the same. Fig. 12 is a bottom plan view of the same. Fig. 13 is an outer end view of the same. Fig. 14 is a plan view of the pedestal brace. Fig. 15 is a longitudinal edge view of the same. Figs. 16 and 17 are opposite end views of the same, and Fig. 18 is a sectional view of the same.

Referring now in detail to the drawings: 1 represents the side frame of what is known as a "Fox" type of truck, which type of

trucks are provided with rigid side frames, as distinguished from the "arch-bar" type, which is a trussed type of truck, and more or less flexible. Side frame 1 is provided, 5 as in most of the trucks of the "Fox" type, with upper and lower flanges, the upper flanges being widest at their central portions to provide a securing means for the cross transoms 2 of the truck, and which upper 10 flanges are cut away at such widened or central portions to provide an opening for the reception of the truck bolster.

As hereinbefore stated, the "Fox" truck illustrated in the drawings is of the type 15 which is provided with a centrally perforated side frame which is adapted to receive helical springs (not shown in the drawings) upon which the ends of the bolster rest. Further description of the essential parts of 20 the "Fox" truck will be found, however, in either of the aforementioned patents, and hence the features of the present invention will now be described. These consist, first, in the bracing of the side frame centrally by means of angles 4 and 5, 4 being the 25 upper angles riveted or otherwise secured to inner faces of the side frames 1 immediately beneath the upper integral flange of the side frame 1; and 5 being the lower angles riveted or otherwise secured to the inner faces of 30 the side frames 1, immediately above the lower integral flanges of the side frame. The lower angles 5 are of greater length than the upper angles 4, for a purpose hereinafter 35 described.

The truck is provided with pedestal brace brackets riveted to the side frames 1 at the inner side of the pedestal 6 to receive the pedestal braces hereinafter described. These 40 brackets are angular in shape, being provided with a horizontal securing flange 7 and a vertical securing flange 8, and being also provided with a vertical column portion 9 at the extreme inner end of the bracket. 45 Flange 8 is extended below the horizontal flange 7 to form a gusset 10 for reinforcing the column portion 9 against the end thrust of the pedestal brace. This column portion 50 9 of the brace bracket is provided with projecting guide lugs 11 and side lugs 12 adapted to engage the pedestal brace, as hereinafter described.

13 is the integral pedestal brace lug forming a downward extension of the pedestal 6, 55 being of modified H section to form proper bearing connections between it and the pedestal brace 14. The pedestal brace bracket and the pedestal brace lug are perforated at 15 and 16 respectively, to receive the brace 60 securing bolt 17, of usual form. A pedestal brace 14 is provided with a pair of jaws 18 at one end adapted to embrace the pedestal brace bracket, and with a perforation 19 at the opposite end adapted to receive and 65 embrace the brace lug 13. The jaws of the

brace 14 are rounded at their outer ends and project toward each other and slightly inwardly, thus forming a contracted opening and inwardly bearing surfaces for the outer face of the brace bracket. The bracket 14 is 70 furthermore provided at its jaw-end with bearing surfaces which project into the contracted opening and outwardly bear against the column portion of the brace bracket, such rounded ends of the jaws, forming 75 bearing surfaces opposing the aforesaid projecting bearing surfaces and adapted to engage the opposite side of the column portion 9 of the brace bracket. The perforated portion or opposite end of the brace 14 is also 80 provided with opposing bearing surfaces which are adapted to engage the opposite faces of the brace lugs. The brace 14 is ribbed or reinforced to strengthen it and is centrally and longitudinally perforated to 85 receive the brace securing bolt 17.

It is thought that the construction when considered in connection with the previous 90 patents on this type of trucks will be well understood; but, briefly described, the advantages are as follows: The supplemental braces or angles strengthen the side frame centrally where it is contracted vertically to reduce the height of the car; this being naturally the weakest part of the side frame, 95 such strengthening is accomplished without increase in size of the side frame. As the railway car has been increased in capacity from, say 60,000 pounds in 1900 to 100,000 pounds in 1910, little or no attention has 100 been paid to the strengthening of this type of truck, but the same has been used practically without change of construction notwithstanding such increase in car capacity. This has been because ordinarily the side 105 frames of these trucks are formed by pressing sheet metal in expensive dies, and an increase in the size of the truck or its shape would render such dies useless.

In order to thoroughly brace the side 110 frames of a truck of this type, it is also necessary that the pedestals 6, mounted at the outer ends of these side frames, be braced against separation or contraction. Heretofore, a simple filler or bar, perforated to receive a retaining or securing bolt has been employed, but while this was efficient in preventing the contraction of the pedestals at 115 their lower ends, it was not efficient in retaining the spreading or separation of the lower ends of said pedestals. It will be noted that the braces herein described at one end completely surround the brace lug, and at their opposite ends they do likewise in effect, through the medium of the brace jaws 120 at their rounded outer portions surrounding the brace bracket, so that the brace herein described restrains either contraction or separation of the pedestal at its lower ends. It will be noted, as shown in the drawings, 125 130

that the brace bracket is by its lower flange riveted to the under side of the lower side or edge of the side frame 1, and by its vertical flange is riveted to the outer face of the side frame 1, and also to the lower angle 5 on the inner face of the frame 1. This brings the lower angle 5, which is a tension member, into play in restraining separation of the lower ends of the pedestal, and into compression in restraining contraction of the lower ends of the pedestal.

Having thus described the invention, what I claim as new and desire to secure by Letters Patent is:—

- 15 1. In a car truck having a side plate, a pedestal at one end, a pedestal brace bracket having a thickened bearing portion and a pedestal brace adapted to abut the inner side of the column portion of the pedestal and to embrace the thickened portion of said bracket to restrain the column against both contraction and separation.
- 20 2. A pedestal brace adapted to embrace one of the column portions of said pedestal, and to partly embrace the other of said column portions of said pedestal to prevent spreading of said column portions, and a bolt passed longitudinally through said pedestal brace and through said column portions.
- 25 3. In a car truck, a side plate, a pedestal in one end of said side plate, a pedestal brace bracket, laterally extending lugs on said bracket, a pedestal brace, one end of said pedestal brace being adapted to engage the pedestal column and said lugs, the other end of said pedestal brace being adapted to embrace the other pedestal column.
- 30 4. In a car truck, a side plate, a pedestal in one end of said side plate, a pedestal brace bracket, a pedestal brace, one end of said pedestal brace being adapted to engage the pedestal column and brace bracket, the other end of said pedestal brace, being adapted to

embrace the other pedestal column, and a bolt passing longitudinally through said pedestal brace and through said pedestal columns and pedestal brace bracket.

5. In a car truck, a side plate having integral flanges, a side plate reinforcement consisting of braces secured to said side plate near to its upper and lower flanges respectively and at its central or load receiving portion only, a pedestal in one end of said side plate, and a pedestal brace adapted to embrace one column of said pedestal and to engage the other column of said pedestal, and a bolt passed longitudinally through said pedestal and columns.

6. In a car truck, a side plate, a brace bracket secured to said side plate, lugs on said brace bracket, and a pedestal brace adapted to engage said lugs and pedestal.

7. In a car truck, a side plate, a brace bracket secured to said side plate, laterally extending lugs on said brace bracket, and a pedestal brace adapted to engage said lugs and pedestal.

8. The combination with a car truck pedestal, of a pedestal brace, said brace being formed with jaws at one end and with an opening at the other end.

9. The combination with a car truck pedestal, of a pedestal brace, said brace being formed with jaws at one end and with an opening at the other end, said jaws projecting toward each other.

10. The combination with a car truck pedestal, of a pedestal brace, said brace being formed with jaws at one end and with an opening at the other end, said jaws having rounded outer ends.

In testimony whereof I affix my signature in presence of two witnesses.

CHARLES A. LINDSTRÖM.
